UNITED STATES PATENT OFFICE

VERA ARKEBAUER, OF RIVERSIDE, CALIFORNIA

DESIGN FOR A RING

Application filed May 31, 1929. Serial No. 31,475. Term of patent 7 years.

To all whom it may concern:

Be it known that I, VERA ARKEBAUER, a citizen of the United States of America, residing at Riverside, in the county of Riverside and State of California, have invented a new, original, and ornamental Design for Rings, of which the following is a specification, reference being had to the accompanying drawing, forming a part thereof.

I claim:—

The ornamental design for a ring substantially as shown.

(Miss) VERA ARKEBAUER.
